DILUENT SEPARATOR

Filed July 27, 1926

By H. A. Colford,

Attorney.

Patented Oct. 25, 1927.

UNITED STATES PATENT OFFICE.

SOUTHWICK W. BRIGGS, OF GLENMONT, MARYLAND.

DILUENT SEPARATOR.

Application filed July 27, 1926. Serial No. 125,209.

The present invention relates to separators, and more particularly to a device for removing diluents from oil, although the device is capable of use where it is desired 5 to effect a separation between any substances having different volatile points or volatilities.

It is well known that in the crank case of a gasoline engine the lubricating oil becomes diluted with portions of the fuel and consequently 10 becomes thinner, less viscous and its stability as a lubricant is impaired. Further, especially in cold weather, water becomes admixed with the oil and this water is a source of trouble due to possibilities of freezing and clogging the lubricating system, 15 forming troublesome emulsions with the oil and causing corrosion of the engine parts.

In this invention the term diluents is understood to include the portion of the fuel 20 which becomes mixed with the oil, the water which may enter the crank case and also other volatile contaminants.

An object of the present invention is to provide a separator of this character where- 25 in the separation may be effected by interposing streams of oil and air at the required temperature for driving off the diluents of the oil, and which collects the oil subsequent to being freed of the diluents so that 30 the oil may be re-used.

Another object of the invention is to provide a device which may be used in connection with an internal combustion engine for treating the diluted oil in the crank case to remove the kerosene and other lighter constituents 35 from the oil and returning the oil in substantially its original condition back to the oiling system of the engine.

A further object of the invention is to provide a separator of this general character which may be mounted on or connected to the exhaust manifold of the engine to utilize the heat of the manifold for tempering 40 the air which is admixed with the oil. 45 to utilize the theory of the evaporation or absorption in the removal of the lighter constituents from the oil, so that the viscosity of the oil may remain substantially constant for a long period of use in the engine.

A still further object of the invention is to provide a separator of this general character which permits of the use of a relatively 50 large quantity of air by volume as compared with that of the oil treated, so that the separation of the diluents from the oil

may be accomplished more completely and at a relatively low temperature.

Another important feature is that the air required for removal of diluent may be drawn through the apparatus, by the 60 suction of the engine taking up the diluent and subsequently passing through the carburetor and to the engine.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a side elevation of the diluent separator for oil shown in the present instance as applied to the side of the tractor and mounted on the exhaust pipe and connected with the carburetor.

Figure 2 is an enlarged vertical section taken through the same, a portion of the exhaust pipe being shown.

Figure 3 is a transverse section taken on the line 3—3 of Figure 2 through the upper part of the device as mounted on the exhaust pipe, and

Figure 4 is a fragmentary transverse section taken through the heating portion of the device mounted on the exhaust pipe, on the line 4—4 of Figure 3.

Referring to the drawing, 10 designates the body portion of an internal combustion engine, such as used on a tractor, and which has an intake manifold 11 and an exhaust manifold 12 to which latter is attached an exhaust pipe 13 which, in the construction of tractors extends vertically upward in rear of the manifolds 11 and 12 and is utilized for the support of the present embodiment of this invention.

According to this invention a circuitous chamber is provided the same comprising a pair of cylinders 14 and 15 which are coupled together at top and bottom by means of an upper head 16 and a lower head 17. The upper head 16 is in the form of a casting having a pair of adjacent cylindrical concavities adapted to fit over the upper ends of the cylinders 14 and 15, and is preferably provided with a packing 18 for sealing the cylinders 14 and 15 in the head 16. The head 16 is provided preferably at its rear side with an air intake pipe or section 19

which, as shown in Figure 1 may be connected to an air filter 20 to insure the passage of air into the pipe 19 which is free of dust and other foreign accumulations so that practically a clear air is passed through the circuitous chamber. The pipe 19 opens into the top of the head 16 immediately above the cylinder 14, so that the incoming air enters the upper end of the cylinder 14. For the purpose of supporting the device, the headers 16 and 17 are provided with stuffing boxes 21 and 22 adapted to closely fit the exhaust pipe 13 and which are adapted to be tightened upon the exhaust pipe for binding the headers thereto and also holding the headers against the opposite ends of the cylinders 14 and 15.

The exhaust pipe 13 thus provides the central portion of the cylinder 14, and the latter is provided with a partition wall or plate 23 disposed diametrically and longitudinally in the cylinder 14 and the plate 23 is divided into two portions which lie at opposite sides of the exhaust pipe 13. The partition plate 23 fits closely up against the inner side of the head 16, so as to effectively divide the upper end of the cylinder 14 into two distinct compartments. One of these compartments opens directly into the pipe 19 to receive the air and the partition plate 23 directs the air downwardly, and terminates in spaced relation above the lower head 17, so that the downwardly moving air is free to pass upwardly about the lower end of the partition plate 23 and rise in the cylinder 14 and at the opposite side of the partition plate and the exhaust pipe 13. In this manner, the air is maintained in contact with the exhaust pipe 13 throughout a distance equal substantially to twice the length of the cylinder 14 for uniformly and thoroughly heating the air before it is permitted to pass from the cylinder 14.

The upper head 16 is provided with an intermediate partition wall 24, which at opposite sides conforms to the curvature of the adjacent portions of the cylinders 14 and 15, but which is terminated in spaced relation to the front wall 25 of the head 16 to form a communicating passage 26 between the cavities of the head 16, so as to intercommunicate the cylinders 14 and 15 at their upper ends through the head 16. The air passing upwardly through the outer side of the cylinder 14 is carried through the passage 26 into the top of the cylinder 15. The head 16 is provided with an outlet pipe 27 adapted for connection with the carbureter and manifold 11 to receive the air from the circuitous chamber after it has passed through both of the cylinders 14 and 15.

The pipe 27 opens into a concentrically positioned coupling 28 arranged in the head 16 above the cylinder 15 and to which is secured a depending pipe 29 which passes

downwardly in the cylinder 15 and is preferably flared or flanged as at 30 at its lower end and in spaced relation to the bottom head 17.

The air entering the top of the cylinder 15 travels downwardly about the pipe 29 and into the lower end of the pipe whence the air is drawn upwardly through the pipe 29 into the outlet pipe 27 to the carbureter. If desired, the pipe 29 may be equipped upon its outer surface with a spiral blade 31. This spiral blade 31 directs the air in a spiral path and consequently causes the air to move downwardly with a whirling action so as not only to thoroughly admix the air, but to throw the heaviest particles carried by the air outwardly against the sides of the cylinder 15, and particularly after the air strikes the flange or flared portion 30. In this manner the heavy particles carried by the air are projected downwardly and outwardly toward the lower end of the cylinder 15, so that the particles may be caught in the conical chamber 32 formed in the lower head 17 beneath the cylinder 15. The chamber 32 is provided with a return pipe 33 for oil or the like which may be carried in the air and which is caught in the chamber 32. The pipe 33 enters the lower portion of the chamber and the latter carries immediately above the pipe a cylindrical screen 34 which supports a deflecting disc 35 of a diameter less than that of the inner wall of the chamber 32, so as to provide an annular space or passage about the disc 35 through which the oil or heavy particles may pass for accumulation in the chamber 32.

The head 16 is provided at its intermediate front wall portion with a connecting nipple 36 to which an oil feeding pipe 37 may be attached for supplying oil to the passage 26 in the head 16. The nipple 36 may be provided with a feed nozzle 38 of any approved type, but which in the present instance is shown as projecting across the passage 27 and provided with an opening 39 at one side remote from the cylinder 14, so that air passing from the cylinder 14 through the passage 26 has an injector action to insure the feeding of the oil through the pipe 37 into the stream of air which flows through the passage 26.

An important feature of the present invention is the fact that the air passages through the chamber are relatively large, so that a great volume of air may be constantly fed through the device, and the oil pipe 37 and its nozzle 39 are relatively small, so that but a small volume of oil is fed into the large volume of air. This insures the more complete breaking up of the oil in the stream of air and the more complete separation of the heavier particles of the oil from the diluting lighter constituents, which are readily taken up as a vapor and

carried by the warm air which is passing through the device.

In the operation of the device the warm air takes up the oil in the passage 26 and is thoroughly admixed with the oil as the mixture passes downwardly in spiral fashion in the cylinder 15. The heavier particles of oil are thrown off against the sides of the cylinder 15 and particularly by the flaring 10 flange 30, so that the heavy oil is collected about the sides of the disc 35 while the air carrying the diluents strikes the disc 35 and are deflected upwardly through the pipe 29 and are carried outwardly through the pipe 15 27 to the carbureter and manifold 11.

The oil entering in the chamber 32 is carried through the screen 34 and pipe 33 back to the crank case of the engine 30, as shown in Figure 1.

The oil in the pipe 37 is carried upwardly therein by any suitable means and may be connected to the fly wheel housing in the ordinary manner, so that a centrifugal force in the oil is relied upon for feeding it upwardly through the pipe 37. Of course, when the installations are varied, pumps or other oil feeding devices well known may be utilized as the present invention is applicable to all types of oil feeding systems which are used with internal combustion engines of various makes.

It is obvious that various changes and modifications may be made in the details of construction and design of the above specifically described embodiment of this invention without departing from the spirit thereof, such changes and modifications being restricted only by the scope of the following claims.

40 What is claimed is:—

1. That method of removing diluents and other volatile constituents from crank case oil, which consists in passing air on its way to the intake manifold of an engine through a heating chamber, admixing the heated air in large volume with a relatively small volume of the oil and forming the admixture into a mist, spirally whirling the admixture of air and oil to prolong the contact of the air and oil and maintain the mist form whereby the heated air may reduce the sur-

face tension of the oil to a point where the diluents are freed from the oil, abruptly reversing the direction of flow of the admixture of oil and air to separate the heavier 55 from the lighter constituents so that the air may carry off the lighter constituents therewith, and collecting the oil freed of its lighter constituents and returning the oil to the crank case.

2. A separator for removing diluents and other volatile constituents from crank case oil, comprising a body portion for receiving air in relatively large amounts by volume and including a spiral directing element for 60 imparting a whirling motion to the air passing through the body, means for admitting crank case oil in relatively small amounts by volume into said body portion for admixture with the air to remove the lighter constituents and diluents from the oil during the whirling of the admixture, a baffle plate at the end of said spiral element for receiving the admixture thereagainst, and means for changing the direction of flow of the admixture effective adjacent the baffle plate whereby the heavier constituents of the oil are collected by momentum upon the baffle plate and the air and lighter constituents are carried off therefrom and freed from the oil. 70

3. A separator for removing diluents and other volatile constituents from crank case oil, comprising a heater adapted to receive a relatively large volume of air to heat the same, a centrifugal separator connected to the heater at one end for receiving the air from the heater, means for admitting a relatively small volume of oil to said end of the separator for admixture with the air, the air and oil adapted to commingle and form a mist 85 in its passage throughout the length of the separator and the heavier particles of oil adapted to be separated by centrifugal force from the lighter constituents and the air, means at the other end of said separator for reversing the direction of the air and lighter constituents to separate the same from the heavier constituents of the oil, and means for collecting the heavier constituents of the oil at said other end of the separator. 90

In testimony whereof I affix my signature.

SOUTHWICK W. BRIGGS.
